Application August 26, 1939, Serial No. 292,105

8 Claims.

(Cl. 101—282)

This invention relates to mechanism for reciprocating the bed of a flat bed and cylinder press.

The demand for higher efficiency in press operation has led to the design of presses running at higher and higher speeds, despite certain factors entering into press operation which tend definitely to limit the maximum permissible operating speed. It is the general object of this invention to extend the limit on press speed by a novel construction and arrangement of parts whereby higher operating speeds may be safely attained than with the constructions known heretofore.

The weight of the reciprocating bed is probably the principal limitation upon press speed, because of necessity for accelerating the bed from rest to maximum speed and then decelerating it to rest twice during each complete operating cycle. For this reason, attempts have been made to reduce the weight of the bed. Here again, however, a limit is imposed by the necessity that the bed be rigid enough to avoid any material deflection under the pressure exerted thereon by the cylinder. Ribbed beds have been resorted to for rigidity but the permissible depth of the ribs is limited by the clearances necessary between the bed and the reversing gears as previously installed. The location of the reversing gears previously employed, furthermore, as well as the character of the reversing hanger carried by the bed, have been such that the inner bed tracks of a four track press have been spaced farther apart than is desirable for preventing deflection of the bed between adjacent supporting tracks.

I have invented a novel mechanism for driving press beds whereby the aforementioned objections to previous constructions are overcome and numerous other advantages and desirable results are achieved. In a preferred form of the invention, I provide a reversing hanger disposed substantially centrally of the bed cooperating with reversing cranks which successively engage the hanger near the ends of the press. I also dispose the gear drive for the reversing cranks and press cylinder on one side of the press. This construction provides a greater depth of free space across the machine below the cylinder than is present in previous press constructions. For this reason, the overall height of the press may be less than was formerly required. The novel construction of the hanger and reversing cranks, furthermore, as well as the location of the reversing gears at one side of the frame, permits the several tracks on which the bed is supported for reciprocation to be spaced substantially uniformly, thereby

reducing the deflection of the bed between tracks by reducing the span between the two inner tracks of a four track press, for example.

Other novel features and advantages of the invention will be more fully pointed out herein-after in the course of the following detailed description and explanation in which reference is made to the accompanying drawings illustrating a present preferred embodiment. In the drawings:

Fig. 1 is a plan view of a press having the invention incorporated therein, showing the parts in position for effecting a return stroke of the bed, parts being omitted for clearness;

Fig. 2 is a sectional view taken substantially along the plane of line II—II of Fig. 1, showing the bed at a point in its printing stroke;

Fig. 3 is a sectional view taken along the plane of line III—III of Fig. 1, showing the parts positioned for a return stroke of the bed;

Fig. 4 is a partial sectional view taken substantially along the plane of line IV—IV of Fig. 3; and

Fig. 5 is a view partly in elevation and partly in section along the plane of line V—V of Fig. 4.

Referring now in detail to the drawings, a press of the flat bed and cylinder type includes side frames 10 and 11 connected at their ends by end castings 12 and 13. The press cylinder 14 has trunnions journaled in bearings 15 mounted in upward extensions 16 from the side frames 10 and 11. The bed 17 is supported reciprocably below the cylinder on tracks 18 carried on a cross beam 19. Roller bearings 20 are disposed between the tracks 18 and the bed and the latter is held on the tracks by gib 21. Bearers 22 on the cylinder cooperate with bearers 23 on the bed as the latter passes beneath the cylinder on a printing stroke, the forms being secured to the bed within a chase 24 as usual. The form rollers of the usual inker are shown at 25, the remainder of the inker construction being omitted since it is not involved in the present invention. The inker is driven by the rack 23a which is carried by the bed at the right-hand edge thereof viewing Figure 3 and whose upper toothed surface meshes with a pinion carried by the inker as well known in the art, whereby to drive the inker first in one direction of rotation upon reciprocation of the bed in one direction and then in the opposite direction of rotation upon reciprocation of the bed in the opposite direction. The bed 17 is provided with the usual ink plate 26.

The construction described so far is conventional and for that reason it is unnecessary to go

into detail concerning it. It will be understood that the bearings in which the cylinder 14 is journaled are raised slightly on the return stroke of the bed to provide a clearance between it and the cylinder, the cylinder rotating continuously in the same direction while the bed moves back and forth beneath it. The mechanism for raising the cylinder bearings will be described in detail later.

The press is driven by a motor 27, a driving chain 28 being trained around a sprocket on the motor shaft and a main driving sprocket 29. The sprocket 29 is secured to a main drive shaft 30 which is journaled in bearings 31 in the webs of the two tracks 18 nearest the side frame 11. A fly-wheel 30a is mounted on the shaft 30. A pinion 32 on the shaft 30 meshes with a bed reversing gear 33 secured to a shaft 34. The shaft 34 is journaled in bearings 35 and 36 formed in the side frame 11 and the adjacent inner track 18. A bed reversing crank 37 is secured to the shaft 34 adjacent its inner end and is provided with a roller 38 journaled on a crank pin 39.

The roller 38 is adapted to engage a hanger 40 depending from the bed 17, in a manner to be described further hereinafter. The hanger comprises a ribbed casting having plane bearing surfaces 41 and 42 disposed at 45° angles to the horizontal.

The pinion 32 also meshes with an intermediate gear 43 secured on a shaft 44. The shaft 44 is journaled in bearings disposed in the side frame 11 and the webs of one of the tracks 18, in the same manner as the bearings 35 and 36. The shaft 44 has secured to it a gear 43a which meshes with a gear 45 secured to one of the trunnions of the cylinder 14. The gear 43 also meshes with a reversing gear 46 secured to a shaft 47. The shaft 47 is journaled in bearings 48 and 49 similar to the bearings 35 and 36 for the shaft 34. The shaft 47 also has a crank 50 at the inner end thereof provided with a crank pin 51 having a roller 52 for engagement with the bearing surface 42 of the hanger 40.

A gear 53 has a grooved collar 54 integral therewith (see Fig. 4) and is splined on a sleeve 55 secured to the shaft 44. The gear 53 meshes with a rack 56 secured to the bed 17 for driving the bed during the constant speed portion of its printing stroke. The gear 53 is shifted axially along the sleeve 55 by means to be described shortly while the bed is being decelerated and reversed after a printing stroke.

The gear 53 also meshes with a gear 57 secured to a shaft 58. The shaft 58 is journaled in bearings 59 in the webs of the two tracks nearest the side frame 11 and is slideable axially therein by the same means which shifts the gear 53. A gear 60 on the shaft 58 has a grooved collar 61 integral therewith and is adapted to mesh with a rack 62 on the bed 17 to effect the reverse stroke of the latter.

A pinion 63 on the shaft 44 meshes with a cam gear 64 secured to a shaft 65. The shaft 65 is journaled in bearings 66 similar to the bearings 59 of the shaft 58. A gear 67 on the shaft 65 has a barrel cam 68 formed integral therewith having a groove 69 therein. A shifter yoke 70 pivoted at 71 to the beam 19 has at one end a follower roller 72 in the groove 69 of the cam 68. The other end of the yoke 70 has a block 73 in the groove of collar 61 formed on the gear 60.

A shifter yoke 74 pivoted on the beam 19 at

5 75 has tongues 76 entering the groove in the collar 54 formed on the gear 53. The shifter yokes 70 and 74 are connected by a link 77 pivoted thereto. Rotation of the cam 68 thus causes simultaneous axial shifting of the gears 53, 57 and 60.

10 The gear 67 meshes with a gear 78 for operating a cam shaft (not shown) or other means for periodically actuating auxiliary control devices such as the valves between the suction feet of the feeder and a vacuum pump (not shown).

15 The cam gear 64 has a groove 79 formed in one side thereof. A crank 80 is rotatable on a stub shaft 81 secured in the web of the track 18 nearest the side frame 11, and has a roller 82 in the groove 79. A gear segment 83 secured to the crank 80 meshes with a pinion 84 secured to a shaft 85. The shaft 85 extends between the side frames 10 and 11, being journaled in bearings 86 therein, the webs of the tracks 18 being bored to admit the shaft. The shape of the groove 79 is such that rotation of the gear 64 causes oscillation of the crank 80 and the segment 83. This oscillation is transmitted to the pinion 84 and shaft 85. The latter has eccentrics 87 which, by means of push rods 88, actuate the bearings 15 supporting the trunnions of the cylinder 14. These bearings are mounted in eccentrics so that partial rotation of the latter raises or lowers the bearings.

20 In explaining the operation of the press bed drive described above it will be assumed that the bed 17 is at the left end of its stroke as indicated in Fig. 2 in chain lines. The reversing gear 33 being driven clockwise by the motor 27, the roller 38 exerts downward pressure on the bearing surface 41 of the hanger, thereby accelerating the bed for a printing stroke (i. e., toward the right in Fig. 2). After half a revolution of the gear 33 the roller 38 departs from the bearing surface 42 of the hanger and at that instant the rack 56 engages gear 53. The design of the cam 68 and the setting thereof on the shaft 65 is such that the gear 53 is in vertical alignment with the rack 56 at this instant. Thus, after being accelerated to maximum speed by the crank 37, the bed moves through the constant speed portion of its travel. 25 During the actual printing portion of the stroke, the cylinder is driven frictionally by its contact with the bearers 23, the teeth of the cylinder gear 45 being appropriately relieved for this purpose.

30 At the instant when the trailing end of the bed passes the vertical central plane through the cylinder 14, the roller 52 is in the position shown in solid lines in Fig. 2, and is thereupon engaged by the bearing surface 42 of the hanger 40. Continued counterclockwise rotation of the crank 50 through 90° to the position shown in chain lines causes the bed to be decelerated. It is then reversed as the crank passes beyond the chain line position.

35 While the bed is being decelerated and reversed by the crank 50, the barrel cam shifts the yokes 70 and 74 to the position shown in Fig. 4, so that the gear 60 is ready to engage the rack 62 to move the bed through the constant speed portion of its travel on the reverse stroke. This engagement occurs when the crank 50 has rotated to a position 180° from that in which it is solid lines in Fig. 2.

40 The cam groove in the gear 79 causes oscillation of the crank 80 and the segment 83 at the

proper time to cause the bearings 15 to be raised so that the cylinder 14 clears the form on the bed when the latter makes its reverse stroke.

When the bed has reached the point in its reverse stroke at which the rack 62 passes beyond the gear 60, the roller 38 of the crank 37 is in the position shown in solid lines in Fig. 2 and engages the bearing surface 41 of the hanger to decelerate the bed on continued clockwise rotation of the reversing gear 33. A full cycle of operations is thus completed and continued operation of the drive involves merely a repetition of the cycle described. It will be understood that the oscillation of the shaft 85 is such as to restore the bearings 15 of the cylinder 14 to the position in which the cylinder has firm engagement with the form on the bed, before the latter reaches the cylinder on the printing stroke. It will also be understood that the movement of the bed is positively controlled throughout its stroke in both directions, so that the racks 56 and 62 mesh properly with the gears 53 and 60 during the constant speed portion of the printing and reversing strokes.

It will be apparent that the invention is characterized by numerous advantages over present bed drives as known heretofore. The use of a hanger having both its bearing surfaces in alignment and the disposition of the reversing gears beyond one side of the press makes it possible to place the inner tracks 18 closer together, thereby equalizing the distance between them with the distance between them and the outermost tracks. This shortens the span of the bed between the inner tracks and limits the deflection of the bed during printing. By way of comparison, the invention permits the distance between the outer and inner tracks to be as much as 90% of the distance between the inner tracks as compared to about 50% for the previous constructions. The maximum and minimum track spacings for a typical example of my invention are 18½" and 17½", compared to 25½" and 13" for the former construction.

By locating the reversing gears beyond the side frame instead of between the inner track webs, it is possible to use gears of larger diameter, thus reducing the tooth pressure and permitting the use of less expensive material such as cast iron, instead of the more expensive heat treated alloy steels. The reversing gears are subject to the tremendous forces involved in rapid acceleration and deceleration of the bed and their strength is a definite limit upon the operating speed of the press. By virtue of the location of the reversing gears beyond the side frame, the tooth width thereof may be increased, further to reduce the unit pressure, without requiring greater spacing between the inner track webs as would be the case if the reversing gears were located therebetween.

The main driving gears, furthermore, may be of the single or double helical type which are particularly advantageous at higher speeds because of greater strength, quiet operation and freedom of vibration. It is not possible to employ this type of gears in press drives as previously constructed.

The closer spacing of the tracks makes it possible to reduce the overall depth of the bed for a given permissible maximum deflection. This reduces the weight of the bed and raises the maximum safe operating speed.

The flywheel shaft is near the center of the press, thereby reducing the gear shock trans-

mitted from the reciprocating type bed assembly to the flywheel drive pinion, and vice versa, to a minimum.

The construction shown also makes it possible to design the cross beam 19 of greater depth than heretofore. This means that the overall height of the machine may be reduced.

The drive gears, being located outside the press frame, may be enclosed in an oil filled housing.

A further advantage of great importance is the fact that there are only two gear meshes between the main drive shaft and the cylinder or the bed. This compares with four or more meshes in previous drives. The lost motion representing cumulative tooth clearances is thus greatly reduced. This minimizes the so-called "bumping" of the register segment usually mounted on the cylinder and register rack on the bed to insure perfect registration on beginning of the printing operation. The reduction in the number of gear meshes also makes the press exceptionally smooth running, which characteristic is reflected in a longer useful life of the press.

It will be noted that the rack 56 through which the bed is driven on a printing stroke is located generally centrally of the bed, whereas the rack 62 through which the bed is driven on a reverse stroke is located adjacent the edge of the bed which carries the inker driving rack 23a. This arrangement has been found particularly advantageous in that it reduces any tendency which the bed might otherwise have to skew upon the reverse stroke. The relatively heavy load imposed upon movement of the bed in a printing stroke is taken by the generally centrally disposed rack 56. On the reverse stroke of the bed the principal load is imposed by the inker, as there is very little resistance to the reverse movement of the bed itself. By positioning the rack 62 adjacent the edge of the bed which carries the rack 23a the force which is consumed mainly in driving the inker on the reverse stroke is applied adjacent the edge of the bed at which such force is transmitted to the inker, thus reducing to a minimum the lateral distance between the points of application of force and hence reducing the tendency of the bed to skew upon the reverse stroke.

Although I have illustrated and described but a preferred embodiment of the invention, it will be understood that changes in the construction and arrangement disclosed may be made without departing from the spirit of the invention or the scope of the appended claims.

55 I claim:

1. In a press, a frame, a bed reciprocable along tracks on said frame, reversing shafts journaled in said frame adjacent the ends thereof, a hanger depending from said bed having inclined plane bearing surfaces extending laterally therefrom, cranks on said shafts having rollers adapted to engage said surfaces respectively when the bed nears the ends of its stroke, gears on said shafts, a main drive shaft deriving its power from outside the press having a pinion thereon meshing with one of said gears, an intermediate shaft having a gear thereon meshing with said pinion and the other of said gears, and a cylinder journaled in said frame for cooperation with said bed, said cylinder being driven directly from said intermediate shaft.

2. In a press, a frame, a bed reciprocable along tracks on said frame, reversing shafts journaled in said frame adjacent the ends thereof, a hanger depending from said bed having inclined plane

bearing surfaces extending laterally therefrom, cranks on said shafts having rollers adapted to engage said surfaces respectively when the bed nears the ends of its stroke, said surfaces and rollers lying in the same plane longitudinally of the press, gears on said shafts, a main drive shaft deriving its power from outside the press having a pinion thereon meshing with one of said gears, an intermediate shaft having a gear thereon meshing with said pinion and the other of said gears, and a cylinder journaled in said frame for cooperation with said bed, said cylinder being driven directly from said intermediate shaft.

3. In a press, a frame, four parallel tracks on said frame extending longitudinally thereof and spaced across the width of the frame, a bed reciprocable along said tracks, the minimum center-to-center distance between adjacent tracks being at least 75% of the maximum center-to-center distance between adjacent tracks, reversing shafts journaled in said frame adjacent the ends thereof, a hanger depending from said bed having inclined plane bearing surfaces extending laterally therefrom, cranks on said shafts having rollers adapted to engage said surfaces respectively when the bed nears the ends of its stroke, gears on said shafts, a main drive shaft deriving its power from outside the press having a pinion thereon meshing with one of said gears, an intermediate shaft having a gear thereon meshing with said pinion and the other of said gears, and a cylinder journaled in said frame for cooperation with said bed, said cylinder being driven directly from said intermediate shaft.

4. In a press, a frame, a bed reciprocable along tracks on said frame, reversing shafts journaled in said frame adjacent the ends thereof, a hanger depending from said bed having inclined plane bearing surfaces extending laterally therefrom, cranks on said shafts having rollers adapted to engage said surfaces respectively when the bed nears the ends of its stroke, gears on said shafts, a main drive shaft deriving its power from out-

side the press having a pinion thereon meshing with one of said gears, an intermediate shaft having a gear thereon meshing with said pinion and the other of said gears, and a cylinder journaled in said frame for cooperation with said bed, said cylinder being driven directly from said intermediate shaft, all said gears being located outside of said frame.

5. In a press, a bed, an inker, means disposed in the vicinity of the longitudinal center line of the bed for driving the bed upon a printing stroke, means carried by the bed at an edge thereof for driving the inker and means disposed adjacent said inker driving means for driving the bed upon a reverse stroke.

6. In a press, a bed, an inker, means for driving the bed upon a printing stroke, means carried by the bed for driving the inker and means for driving the bed upon a reverse stroke, the means for driving the bed upon a reverse stroke being disposed adjacent the inker driving means and nearer such means than the means for driving the bed upon a printing stroke.

7. In a press, a bed, an inker, a rack connected with the bed through which the bed is driven upon a printing stroke, a rack connected with the bed through which the bed is driven upon a reverse stroke and means carried by the bed for driving the inker, the second mentioned rack being disposed adjacent the inker driving means and nearer such means than the first mentioned rack.

8. In a press, a bed, an inker, a rack carried by the bed and disposed in the vicinity of the longitudinal center line of the bed through which the bed is driven upon a printing stroke, a second rack carried by the bed at an edge thereof for driving the inker and a third rack carried by the bed and disposed adjacent said edge of the bed through which the bed is driven upon a reverse stroke.

SAMUEL A. HUFFMAN.
